Specification for Design.

Patented Sept. 21, 1915.

Application filed July 15, 1914. Serial No. 851,179. Term of patent $3\frac{1}{2}$ years.

To all whom it may concern:

Be it known that I, JAMES D. CORCORAN, a citizen of the United States, and a resident of Cleveland, county of Cuyahoga, and State of Ohio, have invented a new, original, and ornamental Design for Grease-Cups and Oilers, of which the following is a specification, reference being had to the accompanying drawing, forming part thereof.

In said annexed drawing: Figure 1 is a side elevation of a grease cup showing my

new design; Fig. 2 is a plan view of the same; and Fig. 3 is a bottom view of the grease cup.

I claim:

The ornamental design for a grease cup and oiler, as shown.

Signed by me this 11th day of July, 1914.

JAMES D. CORCORAN.
